ART OF PACKAGING

Robert G. Peck, Jr., Chicago, Ill., assignor to The
Aridor Company, Chicago, Ill., a corporation of
Illinois

Application August 19, 1939, Serial No. 290,946

1 Claim. (Cl. 215—40)

This invention relates to the art of packaging more particularly with vacuum type containers.

Among other objects, the invention aims to provide an improved package of this class having a more perfect seal between the closure and the container. The invention embraces both means and method for accomplishing this improved result with simplicity, economy and enhanced efficiency of application and operation.

The invention will be understood by reference to the accompanying drawing forming a part of this specification and in which—

Figure 1 is an elevational view of a package embodying the present invention and which may be of full size;

Figure 2 is a bottom plan view of the improved closure shown in Fig. 1;

Figure 3 is a fragmentary cross-sectional view on an enlarged scale of the parts of Figs. 1 and 2 before assembly; and

Figure 4 is a view similar to Fig. 3 but after assembly.

Referring in detail to the drawing the container 10 may be of the usual glass form adapted to carry for merchandising food stuffs which it is desirable to keep out of contact with the air until just before using, at which time the closure or cap 11 is removed.

In practice the food contents are placed in the container 10 and the closure 11 having the gasket 12 is pressed thereon under vacuum, that is, by a pressure applying mechanism which operates while it and the container and closure are all within a hood or bell from which the air has been temporarily exhausted, as is well known in the art and need not be here specifically described.

In accordance with the present invention, the brim 13 of the container 10 is desirably of bulbous bead-like formation and the closure 11 has a rim 14 of U-shape cross-section. As here shown, the closure is of metal and has a disk-like center portion 15 from around which the rim 14 is integrally and annularly embossed to form a relatively deep inverted U-cross-section, the free edge of the closure rim being desirably continuous and turned somewhat inwardly in a direction toward closing the loop of the U. In other words, the cross-section of the rim 14 is made to follow in general the contour of the container brim 13, this construction providing a rim 14 of great rigidity in the nature of a horseshoe or arabic arch.

Before the closure is pressed onto the container as described, the gasket 12 is inserted into the rim 14 of the closure to fill the trough of the U somewhat as shown in Figs. 2 and 3. This gasket 12 is desirably at least semi-plastic and may be of rubber-like material having the capacity not only of stretching but of being permanently deformed under pressure without breaking

or cracking. As is well known in the art, it may be composed of flowed-in latex composition or the like.

When, now, the closure with its gasket is pressed upon the container, as described, and as shown in Fig. 4, the material of the gasket 12 is displaced to make room for the container brim and the gasket material is forced about the brim, directed by the substantially rigid walls of the closure rim, to an extent sufficient to cause the gasket material to contact the opposite sides of the container edge 17 and 18 adjacent or where they join the container brim 13. Thus the gasket is compelled to assume itself a cross-section in the form of a horseshoe arch, forms a somewhat bayonet joint interlock with the brim and provides a continuous film-like sealing medium about the entire contour of the container brim and between the latter and the inner wall of the closure rim closely adjacent to and following said contour.

As will be readily understood, the atmospheric pressure on the exterior of the package, which, due to the vacuum within the package, is not balanced therewith, maintains the parts in the relationship effected as described and, in addition, the novel interlock described contributes materially to this result in an improved manner.

At the same time, when the container is desired to be opened, excessive force is not required to remove the closure from the container, but merely sufficient force to overcome the atmospheric pressure on the exterior of the container plus the resistance to flow of the gasket material, the metal rim of the closure not being in direct contact with the container but serving largely as described to direct the flow of the gasket and to serve as a mold therefor, in addition to its other closure functions.

Having described my invention, I claim—

1. In a container package, the container having a brim of bulbous bead-like cross-section, the combination therewith of a closure having a continuous rim of relatively deep inverted horseshoe-arch cross-section facing downwardly and adapted to receive the brim of the container, the free edge of said rim being turned inwardly in a direction to form the horseshoe-arch cross-section, the said free edge being continuously unbroken adjacent the bead-like brim and following the contour thereof, and a gasket in said rim of at least semi-plastic rubber-like material also of horseshoe-arch cross-section and having an interlock with said brim, said gasket having initially substantially filled said rim and having flowed under pressure about said bead-like brim whereby to acquire said cross-section and provide said interlock in cooperation with said brim and rim.
